J. BAUDINO

ANTISPLASH DEVICE FOR TANKS

Filed Aug. 14, 1922

Inventor

John Baudino.

E. B. McEachern

Attorney

UNITED STATES PATENT OFFICE.

JOHN BAUDINO, OF HERRIN, ILLINOIS.

ANTISPLASH DEVICE FOR TANKS.

Application filed August 14, 1922. Serial No 581,873.

To all whom it may concern:

Be it known that I, JOHN BAUDINO, a citizen of the United States, residing at Herrin, in the county of Williamson and the State of Illinois, have invented certain new and useful Improvements in Antisplash Devices for Tanks, of which the following is a specification.

This invention is an improvement on the anti-splash device shown and described in my application for Letters Patent filed April 12, 1922, and bearing Serial No. 551,899.

While the object of the invention is the same I have simplified the construction and reduced the cost of manufacture.

The device in its present form may be applied either to the exterior of the gas tank or it may be placed within the tank. I have found by experimentation that the result obtained is satisfactory with either method of installation. When placed on the outside fewer parts are required and it is easier to remove for cleaning. But in some types of automobiles it is not practical to place the device on the exterior of the tank, and it is therefore necessary in such cases to place it on the inside.

In the drawing:

Figure 1 is a vertical sectional view showing the device applied to the exterior of the tank.

Figure 2 is a similar view showing it placed within the tank.

In the drawing A designates the tank. My device consists of a cylinder 1 having cross partitions 2 which are spaced apart and provided with openings 3. Connected to said partitions are conical diaphragms 4. The apex portions of the diaphragms are slotted as at 5 and that portion or strip of material between the slots is forced outwardly, leaving laterally opening vapor passages, centrally obstructed by the strips 6.

When placed on the outside of the tank 45 the cylinder 1 is threaded to a hollow stem 7, upon which is placed a packing nut 8 and packing 9. At the end opposite the stem 7 the cylinder has an interior boss 10 into which is threaded a pipe 11 which conveys fumes from the tank to the gas saver, not shown, and which is connected to the engine. An air vent 12 is provided through which the fumes escape to the outer air when the engine is not running and through which 55 air is drawn when the engine is in operation.

When this device is placed within the cylinder it is inverted as shown, and I employ a slightly different form of stem 7^a and the pipe 11 instead of being connected directly to the cylinder is connected to a gas chamber 13, having a vent 14, and which is threaded on the stem 7^a as shown.

The method of placing the device in position either outside of or within the tank is 65 clearly brought out in the drawing which forms a part of this application.

What I claim is:—

The combination with a gas tank having a hollow exteriorly threaded stem, of a cylinder adapted to be secured to said stem either upon the outside or the inside of the tank, the cylinder being inverted when in the last mentioned position, perforated partitions carried by the cylinder, slotted cones 75 therein co-operating with said partitions, a pipe adapted to receive fumes from said cylinder, and means for admitting air to said gas fumes prior to their entry into said pipe, said means also affording an escape 80 for the fumes when suction through said pipe is cut off, as and for the purpose set forth.

In testimony whereof I affix my signature.

JNO. BAUDINO.
